UNITED STATES PATENT OFFICE.

ROBERT F. METCALFE, OF ERIE, PENNSYLVANIA, ASSIGNOR, BY MESNE ASSIGNMENTS, TO SOCONY BURNER CORPORATION, OF WILMINGTON, DELAWARE, A CORPORATION OF DELAWARE.

BURNER-CONTROLLING APPARATUS.

Application filed October 2, 1922. Serial No. 591,767.

To all whom it may concern:

Be it known that I, ROBERT F. METCALFE, a citizen of the United States, residing at Erie, in the county of Erie and State of Pennsylvania, have invented new and useful Improvements in Burner-Controlling Apparatus, of which the following is a specification.

This invention is designed to facilitate the control of a burner and is particularly desirable in such burners as are adapted for domestic use. With such burners it is desirable to automatically start and stop the burners from some control such as a thermostat. This has heretofore been effected. It is also desirable to provide means which will positively stop the burner irrespective of the action of the thermostat provided there is any failure of the burner and it is desirable in this connection to prevent a re-starting of the burner except through manual operation so that it may be observed by the operator. In this connection also it is desirable as the feeding mechanism of the burner is stopped to positively close off the fuel feeding passage to effect an immediate stoppage of flow. These desirable functions are performed with the apparatus of the present invention. Other features of the invention will appear from the specification and claims.

The invention is illustrated in the accompanying drawings as follows:—

Fig. 1 shows a central sectional view through the burner.

Fig. 2 a section of the burner actuating and controlling mechanism along the line 2—2 in Fig. 1.

Fig. 2^a a detail view of the control motor controlling switch.

Fig. 3 an elevation of the burner control safety switch.

Fig. 4 a section on the line 4—4 in Fig. 3.

Fig. 5 a rear view of the controlling motor and its connections.

Fig. 6 a diagram of the wires.

1 marks the burner chamber. This has a confined nozzle 2, 3 marks the fuel jet, 4 the supply passage leading to the fuel jet, and 5 the air jet by which the fuel is sprayed and drawn to the fuel jet. The air under pressure is conveyed through a pipe 6. Ignition is accomplished by the use of a spark plug 7. Added air for combustion is delivered through the action of a fan 8 which is fixed

on a shaft 9. A passage 10 connects the fan with the rear end of the burner, the air passing by a spider 11 through a space 12 around the ignition cone 13. There is a preliminary combustion of rich mixture at the center of the burner which is enveloped by the air entering at 12 and a very rapid intense combustion at the issuance of the nozzle 2. These particular features do not form a part of the invention of this application except as they may be connected with the features hereinafter described, the same forming the subject matter of application filed by me Oct. 2, 1922, Serial Number 591,769, method and burner for burning liquid fuel. The fan is carried in a frame 14 on which the driving motor 15 is mounted, the motor shaft 16 being connected by a coupling 17 with the shaft 9. The shaft 9 is carried in bearings 18 in a frame extension 19. A worm 20 on the shaft 9 operates in a worm gear 21 arranged on a shaft 22. An eccentric 23 is fixed on the shaft 22. A strap 24 operates on the eccentric. A connecting rod 25 extends from the strap to the piston 26 of the air pump. The piston operates in a cylinder 27. The cylinder has an inlet valve 28 and a discharge valve 29 and discharges to a receiver 30 arranged over the cylinder. A pipe 31 leads from the fan chamber to the inlet valve 28 so that it retains air from the same source as the fan if desired. The pipe 6 leads from the receiver 30. A shell 32 is arranged around the burner 1 forming an air space. This air space, however, is in communication with the burner and subjected to its variations in pressure. An opening 33 (see dotted lines, Fig. 1 and Figs. 3 and 4) leads from this air space and is closed by a swinging plate 34. The plate 34 is hinged at 35 in a fitting 35^a. The plate is provided with an adjustable weight 36 in the form of an enlarged head of a screw which is screwed through the plate. The screw is locked in adjustment by a second screw 37 which springs the part of the plate through which the screw 36 extends. A wire 38 leads to a fitting 35^a and consequently to the plate 34. A contact point 39 is carried by the plate 34 and operates in connection with a contact 40 carried by a plate 41 on a post 42, the post 42 being supported by but insulated from the fitting 35^a. A wire 43 extends from the post 42. A con-

tact point 44 is also carried by the plate 35 and is adapted to swing into contact with the point 45 on a post 46, the post being mounted on but insulated from the fitting 35. A wire 47 extends from the post 46.

This safety device simply exemplifies a form of safety device which will respond to a failure of the burner. If when the burner motor starts there is a failure of ignition 10 the pressure on the swinging plate 34 will not be sufficient to carry the point 39 out of contact with the point 40 and through a controlling motor controlling the controlling apparatus hereinafter described the burner 15 motor will be shut down after a fixed interval. If, however, there is a proper ignition the expansion due to temperature in the burner creates a decided back pressure which communicated to the plate 34, swings the 20 point 39 out of contact with the point 40 and the contact 39 into contact with the point 45 which position will so operate on the controlling apparatus as to permit a continuation 25 of the operation of the burner motor.

25. A controlling motor 48 is mounted in a case 48^a supported on the frame 14. It drives a series of gears 49 which drive the switch shaft 50. A cam 52 is fixed on the shaft 50. A switch arm 53 is hinged at 54 30 on a plate 54^a supported by but insulated from the frame. This has a riding wheel 55 which rides on the cam 52. A contact point 56 is carried by the switch arm 53 and is adapted to be brought into contact with a point 57 when the cam roller 55 is on a raised portion 58 of the cam 52. The point 57 is carried by a spring arm 60 and a spring 59 operates on the arm 53 and tends to separate the points 56 and 57 when the roller 55 40 drops the raise 58 of the cam. A wire 61 leads from the plate 54^a to a plate 62. A wire 63 leads from the plate 62 to the motor 15. The spring support 60 is mounted on a conductor plate 64. A wire 65 leads from 45 the plate 64 to a plate 66 and a wire 67 leads from the plate 66 to a post 68. The line wire 69 connects the post 68. The other line wire 70 leads to a post 71. A wire 72 leads from the post 71 to a fuse block 73. A wire 50 74 leads from the fuse block to a plate 75 and a wire 76 leads from the plate 75 to the other side of the motor 15. It will readily be seen, therefore, that when the points 56 and 57 are open the motor is stopped. When 55 these points are together current is on the motor so as to drive the fan and air pump.

60. The wiring can be better understood from an observation of the diagram in Fig. 6 from which the purpose of the connections on the regular apparatus will be readily apparent. In order to operate the controlling motor so as to control the burner motor there are three points of control. First, the safety switch which I have described which responds to different pressures in the burner

and consequently takes care of a failure at the burner. A switch operated by a thermostat so as to automatically control the temperature of whatever may be heated by the burner, and a manually controlled switch 70 which must be operated in order to start the apparatus after there has been a failure and a stoppage through the action of the safety switch. The manually operated device is taken care of by a push button switch 77. 75 The thermostat is indicated at 78 and the safety switch has the plate 34 shown diagrammatically and the contacts 39, 40 and 44 indicated.

The thermostat operates the thermally movable sensitive element 79 carrying the movable point 80 of the switch. It operates against a point 81 when the thermostat is subjected to cold temperature and this is commonly called the cold side and contacts 85 a point 82 when the thermostat is subjected to a warmer temperature and this is ordinarily referred to as the warm side.

A series of contact posts 83, 84, 85, 86 and 90 87 are grouped around the switch shaft 50 and are in position to be wiped and bridged by a bridge 88 which bridge is carried on a stop disc 88^a on the shaft. With the bridge over the posts 83 and 84 the controlling apparatus is so set as to continue the operation 95 of the burner motor. When the bridge is over the posts 86 and 87 the apparatus is in position to stop or open the circuit through the burner motor. Otherwise this is the normal stopped position. When the bridge is 100 crossing the posts 84 and 85 this will stop the burner motor and may be termed the emergency stop position. The stoppage here takes place only when there is a failure of ignition and an operation of the safety 105 switch. To start the motor again requires the operation of the push button 77.

The line wire 70 leads to a post 89 from which a wire 90 leads to the control motor 48. The wire 69 leads to a post 91 from which a wire 92 leads to a contact post 93 of a magnetic switch, the switch being provided with the usual swinging arm 94 which is connected by a wire 95 with the motor 48. A coil 96 controls the arm 94.

A transformer 97 is provided, a wire 98 in the low tension side running directly to the post 84 of the control switch. The other side has a wire 99 running to the coil 96, from the coil 96 by a wire 100 to a post 101, from the post 101 by a wire 101^a to a contact plate 102 forming one side of the switch controlled by the push button 77. A bridge 103 operates on the plate 102 and a plate 104. A wire 105 leads from the plate 104 to a post 106. A wire 107 extends from the post 106 to a post 108 which is connected with the movable element 79 of the thermostat. A wire 109 leads from the plate 82 at the warm side of the thermostatic switch 110

to a post 110 and the wire 47 leads to this post. A wire 110^a leads from the post 110 to the post 83 of the controlling switch. A wire 111 leads from the plate 81 at the cold 5 side of the thermostatic switch to a post 112 and a wire 113 leads from the post 112 to the post 86 of the control switch. The wire 43 leads to a post 114. A wire 115 leads from the post 114 to the post 85 of the control 10 switch. A wire 116 also leads from the post 114 to a contact plate 117 adapted to be connected with the bridge plate 103 while the stem of the push button remains in contact with the plate 102 thus bridging the 15 wires 101^a and 116. A wire 84^a permanently bridges the posts 84 and 87.

In order to lock the switch 93—94 in closed position as the stop disc 88^a rotates bringing the bridge plate from one set of 20 contacts to another I provide the following mechanism:—The switch arm 94 is provided with an insulated block 94^a through which the contact screw 94^b extends forming the immediate contact with the point 93. The 25 flexible wire 95 extends from the screw 94^b. The arm 94 is pivoted at 94^c and is provided with a weight 94^d which throws the switch open when the circuit through the coil 96 is broken. The arm 94 has a catch extension 30 94^e. A catch lever 94^f is pivoted at 94^g on the frame and carries a catch shoulder 94^h which is adapted to swing down back of the extension 94^e when the arm 94 is drawn down by the magnetic coil. The lever 94^f 35 has a cam extension 94ⁱ which is in the path of studs 94^j carried by a disc 94^k, the disc 94^k being mounted on the switch shaft 50. The lugs 94^j are so positioned as to lift the lever 94^f out of engaging position when the 40 switch plate 88 is in position to bridge the contacts 83—84, or the contacts 84—85, or the contacts 86—87. At all other positions the lever is released from the pins 94^j and drops under the influence of the weight of 45 the lever in position to lock the switch lever in closed position providing it has been brought to closed position, the lever freely permitting the closing movement of the lever 94 to take place at any time.

50 The operation of the controlling apparatus through these controlling circuits is as follows:—As shown the control shaft is stopped with the bridge plate 88, bridging the posts 83 and 84 and this is in the normal 55 running position, in other words the control motor is at what may be termed the running position. Under these conditions the thermostatic switch would either be closed on the cold side or be in an intermediate position. 60 As shown it is on the cold side and the safety switch 34 initially would be swung outwardly under the pressure due to combustion within the burner chamber 1 closing the points 44 and 45. Under these conditions following the circuit through the

magnetic switch coil 96 we find that this circuit is open and consequently the switch 93—94 open and the controlling motor closed. Tracing this circuit the wire 99—98 leads to the contact 94, across the bridge 70 88, post 83, by the wire 110^a to the post 110, by the wire 109 to the warm side of the thermostat where we find the points 82 and 80 separated and consequently a break in the circuit. Under these conditions also the contacts 44—45 are closed under pressure from the burner and there is a break between the points 39—40 so that there is nothing at the safety switch that will change this condition. If anything, however, should happen to the burner such as failure in ignition, or failure in fuel immediately the pressure incident to the burning gas in the burner would be relieved and the safety switch would reverse due to the weight 75 bringing the points 39—40 together. Following the circuit thus established through the magnetic coil 96 the wire 99—98 leads to the point 84, by the bridge 88 to the point 83, by the wire 110^a to the post 110, by the wire 47 through the points 40—39, by the switch plate 34, wire 38 to the post 106, by the wire 105 past the push button switch by way of the point 104, bridge plate 103 and point 107, thence by the wire 104^a to 80 the wire 101^a to the post 101, thence by the wire 100 to the coil 96. It will be seen, therefore, that the magnetic switch will be immediately closed and the controlling motor is started advancing the switch plate 88 counter-clockwise. Immediately 85 this starts as before stated the lever 94 being in its lower position the catch lever 94^f locks the lever 94 in closed position until the bridge plate 88 bridges the contacts 84—85. At this point the lock lever 94^f is lifted by the pin 94^l and if the other conditions remain the same permits the opening of the controlling switch 93—94. That this is so 90 is evident by following the line through the controlling coil 96 of the magnetic switch. The wire 99—98 will lead to the post 84, by the bridge 88 to the post 85, by the wire 115 to the post 114, by the wire 43 to the point 45, the switch 45—44 being open. This 95 opening breaking the circuit the magnetic switch is opened and the controlling motor stops with the bridge plate 88 bridging the posts 85—84 and remains in that position 100 until the apparatus is started by a manual operation of the push button 77. With the push button moved inwardly so as to bring the plate 103 into contact with the point 117 a circuit is established through the coil 105 115 96 as follows:—By the wire 99—98 to the point 84, by the bridge plate 88 to the point 85, by the wire 115 to the post 114, by the wire 116, point 117, bridge plate 103, stem of the push button, plate 102, wire 101^a, post 101, wire 100 to the coil. The control- 120 125 130

ling switch, therefore, is immediately closed by a movement of the push button and as soon as the control motor starts the lock lever operates and locks the switch 93-94 in closed position until it reaches a position over the points 86-87. When the plate reaches this position it will stop at this position, or continue to running position depending on the condition of the thermostatic switch. It will be understood that with the switch plate 88 over the posts 84-85, or over the posts 86-87, the points 56-57 are separated and the burner motor has been stopped.

If the thermostat is at the cold side a circuit will be established through the coil 96 of the magnetic switch so as to hold this switch in closed position through the influence of the coil and the controlling motor will continue. Following this circuit it will be seen that it will pass from the coil 96 by the wire 99-98, post 84, bridge wire 84^a, post 87, bridge plate 88, post 86, wire 113 to the post 112, wire 111 to the point 81, across to the point 80 by way of the thermal element 79, terminal mounting of the thermal element 108, wire 107 to the post 106 by wire 105, and with the pressure on the push button released by way of the plates 104, 103, 102, wire 101^a, post 101, wire 100 to the coil. If the push button is retained in depressed position then, of course, the bridge plate will remain stationary on the posts 86-87 until the release of the push button. If, however, the thermostatic movable element 79 has the switch point 80 away from the cold side, or on the warm side, then the circuit will be broken with the plate 88 on the posts 86-87 and then will remain in the stopped position until the reversal of the thermostatic element. That this is evident will be seen by following the circuit from the controlling coil 96 to the wire 99-98, post 84, bridge wire 84^a post 87, bridge plate 88, post 86, wire 113, post 112, wire 111 to the point 81 where there will be a break in the circuit and this break will continue until the point 80 is brought to the cold side and in contact with the point 81. If, however, the point 80 is brought to the warm side so that this circuit is closed and the controlling motor is started by the closing of the circuit just traced the contact between the points 56-57 is made by the cam 52 with the initial movement away from the posts 86-87 and the burner motor is started. The controlling motor has the usual retarding device so that by the time the plate 88 reaches a position to bridge the points 83-84 there will have been a sufficient interval for the burner to start and the expansion due to the burning gases to have acted on the safety switch to close the points 44-45. If due to the failure of ignition a circuit is established through the coil 96 of the magnetic switch by way of

the points 39-40 it will continue the operation of the controlling motor to run it over to the safety stop position over the posts 84-85. That this is so is evident by tracing the circuits through the coil 96 by way of the wire 99-98 to the post 84, by plate 88, post 83, wire 110^a, point 40, point 39, safety switch plate 34, wire 38, post 106, wire 105, plates 104, 103, 102, wire 101^a, post 101, and wire 100 to the coil. Under these conditions the controlling motor switch will remain closed and the plate 88 will be brought forward, the locking lever immediately operating and locking it in position until the plate bridges the contact 84-85 where the locking lever is released and the circuit through the coil 96 being broken the controlling switch 93-94 controlling the motor is stopped and the points 57-56 being open at this position the burner motor is stopped. That this is true will be seen by following the circuit from the coil 96 by way of the wires 99-98, post 84, plate 88, post 85, wire 115, post 114, wire 43, point 45 where there is a break in the circuit between the point 45 and point 44. As before stated the parts will remain in this position until the push button is operated and the circuit again closed and the controlling motor put in motion.

Auxiliary devices are shown in diagram in Fig. 6. A transformer 118 is connected with the line wires 69-70 by wires 119 and 120. The low tension side wire 121^a leads to ground and a wire 121 to a post 122 where it is connected through a wire 123 with a circuit breaker 124. Wires 125 lead from the post 122 to a condenser 126. The circuit breaker is connected to the wire 125 and the condenser with a wire 127 by a post 126^a. A wire 128 leads from the post 126^a to a spark coil 129 which is grounded at 130 and connected by a wire 131 with one side 132 of the spark plug 7. The other side 133 is grounded at 134.

It is desirable to immediately stop the flow of fuel when the burner motor circuit is broken in order that there may be no leakage to the burner, or any unconsumed oil delivered to the burner. This is accomplished automatically in the following mechanism: The air pipe 6 leads to and from a chamber 135 having an inlet 136 and outlet 137. A valve 138 closes the passage from the chamber 135 to the outlet by gravity. An armature 139 is mounted on the stem of the valve 138 in position to be actuated by the coil 140. The coil 140 is connected by a wire 141 with the wire 76 and a wire 142 with the wire 61-63, in other words, the coil 140 is in a shunt line with the burner motor circuit. When the burner motor is shut off, therefore, the valve 138 drops immediately closing the air passage 6 and thus immediately cutting off any after-flow.

of fuel by reason of any residual pressure there may be in the receiver or otherwise.

The confined nozzle is desirable with this safety valve in that it not only improves the combustion by bringing the air and gases which are formed from the fuel into more intimate relation but increases the difference in pressure between that existing when there is a failure of the burner and when there is combustion in the burner.

What I claim as new is:—

1. In a burner controlling apparatus, the combination of a burner; a burner motor; a rotating control motor controlling the burner motor, a switch controlling the control motor for a normal operation of the burner; and a safety switch responsive to a burner condition controlling the control motor with an abnormal burner condition.

2. In a burner controlling apparatus, the combination of a burner; a burner motor; a rotating control motor controlling the burner motor; and an automatic re-setting safety switch responsive to a burner condition controlling the controlling motor.

3. In a burner controlling apparatus, the combination of a burner; a burner motor; a rotating control motor controlling the burner motor; and an automatic re-setting safety switch responsive to burner pressures controlling the controlling motor.

4. In a burner controlling apparatus, the combination of a burner; a burner motor; a rotating control motor controlling the burner motor; a safety switch responsive to burner conditions controlling the controlling motor; and a manually controlled re-starting switch acting on the controlling motor after a stoppage by the safety switch.

5. In a burner controlling apparatus, the combination of a burner; a burner motor; a controlling motor controlling the burner motor; a safety switch responsive to burner conditions, said safety switch normally closing a normal running circuit; a second circuit with an abnormal condition of the burner; and a manually controlled re-starting switch acting in conjunction with said second circuit to start the controlling motor after a stoppage by the safety switch.

6. In a burner controlling apparatus, the combination of a burner; a burner motor; a rotating control motor controlling the burner motor; a safety switch responsive to burner conditions controlling the controlling motor; and a thermally controlled switch responsive to a temperature controlled by the burner acting on the control motor.

7. In a burner controlling apparatus, the combination of a burner; a burner motor; a controlling motor controlling the burner motor; a safety switch responsive to burner conditions controlling the controlling motor; a thermally controlled switch responsive to

a temperature controlled by the burner acting on the control motor; and a manually controlled re-starting switch acting on the control motor after a stoppage by the safety switch.

8. In a burner controlling apparatus, the combination of a burner; a burner motor; a controlling motor controlling the burner motor; a safety switch responsive to burner conditions, said safety switch normally closing a normal running circuit; a second circuit with an abnormal condition of the burner; a manually controlled re-starting switch acting in conjunction with said second circuit to start the controlling motor after a stoppage by the safety switch; and a thermally controlled switch responsive to a temperature controlled by the burner acting on the control motor.

9. In a burner controlling apparatus, the combination of a burner; a burner motor; a control motor having a running stop position, an emergency stop position, and a normal stop position, a switch controlling the burner motor closed by the control motor at the running stop position and open at the emergency and normal stop positions; and a safety switch responsive to burner conditions acting on the control motor to prevent its stopping in running stop position when there is a failure of the burner.

10. In a burner controlling apparatus, the combination of a burner; a burner motor; a control motor having a running stop position, an emergency stop position, and a normal stop position; a switch controlling the burner motor closed by the control motor at the running stop position and open at the emergency and normal stop positions; and a safety switch responsive to burner conditions acting on the control motor to prevent its stopping in running stop position when there is a failure of the burner there being an interval between the normal stop position of the control motor and the running stop position for the safety switch to respond to burner conditions as soon as the control motor reaches the running stop position.

11. In a burner controlling apparatus, the combination of a burner; a burner motor; a control motor having a running stop position, an emergency stop position, and a normal stop position; a switch controlling the burner motor closed by the control motor at the running stop position and open at the emergency and normal stop positions; a safety switch responsive to burner conditions acting on the control motor to prevent its stopping in running stop position when there is a failure of the burner; and a manually controlled re-starting switch acting on the control motor after a stoppage in the emergency stop position.

12. In a burner controlling apparatus, the

- combination of a burner; a burner motor; a control motor having a running stop position, an emergency stop position, and a normal stop position; a switch controlling the burner motor closed by the control motor at the running stop position and open at the emergency and normal stop positions; a safety switch responsive to burner conditions acting on the control motor to prevent its stopping in running stop position when there is a failure of the burner; and a thermally controlled switch responsive to a temperature controlled by the burner acting on the control motor to control its movement between the normal running stop position and the normal stop position.
13. In a burner controlling apparatus, the combination of a burner; a burner motor; a control motor having a running stop position, an emergency stop position, and a normal stop position; a switch controlling the burner motor closed by the control motor at the running stop position and open at the emergency and normal stop positions; a safety switch responsive to burner conditions acting on the control motor to prevent its stopping in running stop position when there is a failure of the burner; a manually

controlled re-starting switch acting on the control motor after a stoppage in the emergency stop position; and a thermally controlled switch responsive to a temperature controlled by the burner acting on the control motor to control its movement between the normal running stop position and the normal stop position.

14. In a burner controlling apparatus, the combination of a burner; a burner motor; means driven by the motor delivering air to the burner for combustion; fuel feeding means actuated by the burner motor comprising a controlling passage; a valve in the passage; an electrically controlled device controlling the valve; a rotating control motor controlling the burner motor; means responsive to burner conditions controlling the control motor, a manually controlled switch for re-starting the control motor after a stoppage by the switch responsive to burner conditions; and a thermally controlled switch responsive to temperatures controlled by the burner controlling the control motor.

In testimony whereof I have hereunto set my hand.

ROBERT F. METCALFE.
